UNITED STATES PATENT OFFICE

95,785

DESIGN FOR A ROLLER SKATE

Edward Earle Whitney, Worcester, Mass., assignor to Matthews Manufacturing Company, Worcester, Mass., a corporation of Massachusetts

Application March 28, 1935, Serial No. 56,101

Term of patent 7 years

To all whom it may concern:

Be it known that I, Edward Earle Whitney, a citizen of the United States, residing at Worcester, in the county of Worcester and State of Massachusetts, have invented a new, original, and ornamental Design for Roller Skate, of which the following is a specification, reference being had to the accompanying drawing, forming part thereof.

Fig. 1 is a plan view of a roller skate;

Fig. 2 is a side elevation thereof, and Fig. 3 is a rear elevation thereof, showing my new design.

The dominant feature of the design resides in the wheel guards.

I claim:

The ornamental design for a roller skate as to the accompanying drawing, forming part shown and described.

EDWARD EARLE WHITNEY.
